UNITED STATES PATENT OFFICE

106,304

DESIGN FOR A DRESS ENSEMBLE

Ida Lampel, New York, N. Y.

Application August 12, 1937, Serial No. 71,017

Term of patent 3½ years

To all whom it may concern:

Be it known that I, Ida Lampel, a citizen of the United States of America, residing in New York city, in the borough of Manhattan, county and State of New York, have invented a new, original, and ornamental Design for a Dress Ensemble, of which the following is a specification, reference being had to the accompanying drawing, forming part thereof, wherein,

The rear jacket portion is conventional.

I claim:

The ornamental design for a dress ensemble, substantially as shown, and described.

IDA LAMPEL.
